UNITED STATES PATENT OFFICE.

HJALMAR G. CARLSON, OF WORCESTER, MASSACHUSETTS, ASSIGNOR TO ROCKFORD SPRINKLER COMPANY OF MASSACHUSETTS, OF WORCESTER, MASSACHUSETTS, A CORPORATION OF MASSACHUSETTS.

NUT.

1,116,241.

Specification of Letters Patent.

Patented Nov. 3, 1914.

Application filed July 11, 1912. Serial No. 708,902.

To all whom it may concern:

Be it known that I, HJALMAR G. CARLSON, a citizen of the United States, residing at Worcester, in the county of Worcester and 5 Commonwealth of Massachusetts, have invented a new and useful Improvement in Nuts, of which the following is a specification, accompanied by drawings forming a part of the same.

10 My present invention relates to an improved nut capable of being constructed of sheet metal, and it relates particularly to that class of nuts which are used to form a cap or finish for the ends of metallic pipes 15 employed as conduits.

My invention is carried into effect as hereinabove described, the novel features being pointed out in the annexed claims.

Referring to the accompanying drawings, 20 Figure 1 represents in central sectional view one end of a metal pipe having one of my improved nuts applied to its end. Fig. 2 is a side view of the nut detached from the pipe. Fig. 3 is an end view of the same. 25 Fig. 4 represents the blank from which a nut embodying my invention is made. Fig. 5 represents the blank in edge view. Fig. 6 is a central sectional view of a cup shaped blank from which the nut is made, said cup 30 shaped blank being formed from the sheet metal blank shown in Figs. 4 and 5. Fig. 7 is a central sectional view of the cup shaped blank from which my improved nut is made and having at one end a right angled inter- 35 nal flange. Fig. 8 represents the same view as shown in Fig. 7 but with an internal screw thread. Fig. 9 is a central sectional view of the completed nut.

Similar reference characters refer to 40 similar parts in the different figures.

Referring to the drawings, 1 denotes one end of a piece of pipe such, for example, as is employed as a conduit for electrical wires. One end of the pipe 1 is provided 45 with an external screw thread 2 to receive a nut 3 embodying my present invention, said pipe and nut being shown in central sectional view.

In the construction of my improved nut I 50 take a circular disk of sheet metal 4, shown in plan view in Fig. 4 and in edge view in Fig. 5. By means of appropriate punches and dies, I shape the blank 4 into a cup shaped blank 5 having a cylindrical side 5^a, 55 with one end open at 6 and having its op-

posite end provided with a central hole 7 and having its corners 8, 8 slightly rounded. In forming the cup shaped blank 5 I employ punches and dies of suitable shape to draw the sheet metal disk 4 into a cup 60 shape with a series of external ribs 9, in the present instance eight in number, preferably arranged with equidistant spaces. The ribs 9 enable the periphery of the nut to be seized by a wrench.

The interior of the cup shaped blank is provided with a series of recesses 10, 10 formed on the inside of the cup and exactly opposite the external ribs 9. The outer ribs 9 extend substantially the entire length 70 of the nut, while the inner recesses 10, 10 extend from the open end 6 through that portion of the nut which is cylindrical, or from the open end 6 to the rounded corner 8.

The partially closed end of the cup shaped blank 5 is flattened to form an interior flange 11 substantially at right angles with the side of the cup. A screw thread 12 is next formed in the interior of the cup, 80 the threads being cut as near as may be to the interior flange 11, as represented in Fig. 8. The flange 11 is then turned inwardly and upwardly forming a U-shaped bend 13 and bringing the edge 14 of the flange 11 85 into a horizontal plane at right angles with the axis of the nut, as shown in Fig. 9. In turning the flange 11 inwardly, its edge 14 is brought slightly beyond the first screw thread 16, or far enough to cover the blank 90 space 17, Fig. 8, in the interior of the nut.

When the nut is applied to the end of a pipe, as shown in Fig. 1, the side 5^a of the nut is screwed on the outside of the pipe, with the interior screw threads 12 engaging 95 the exterior screw threads 2 on the pipe. The edge 14 of the flange 11 is parallel with the squared end 18 of the pipe 1 and, inasmuch as the interior screw threads 12 extend into the nut beneath the flange 11, the 100 end 18 of the pipe may be screwed firmly against the edge 14 of the flange on the nut.

The recesses 10, 10 are substantially semi-circular in cross section and they serve to gather in any dirt or iron chips that may 105 rest upon the external screw thread 2 while the nut is being screwed upon the pipe.

I claim,

1. As an article of manufacture, a nut having an internal screw thread, the nut be- 110

ing formed with a series of external longitudinal ribs and a series of internal longitudinal recesses opposite the ribs.

2. As an article of manufacture, a nut 5 having an inturned flange at one end and an internal screw thread extending inwardly from the opposite end, the nut being formed with a series of external longitudinal ribs and a corresponding series of internal longitudinal recesses located opposite the ribs. 10

3. As an article of manufacture, a nut having an inturned flange at one end and

an internal screw thread extending inwardly from the opposite end, the screw 15 thread extending beyond the inner end of the inturned flange, the nut being formed with a series of external longitudinal ribs and a corresponding series of internal longitudinal recesses located opposite the ribs. 20

Dated this fifth day of July 1912.

HJALMAR G. CARLSON.

Copies of this patent may be obtained for five cents each, by addressing the "Commissioner of Patents
Washington, D. C."

Correction in Letters Patent No. 1,116,241.

It is hereby certified that the assignee in Letters Patent No. 1,116,241, granted November 3, 1914, upon the application of Hjalmar G. Carlson, of Worcester, Massachusetts, for an improvement in "Nuts," was erroneously described and specified as "Rockford Sprinkler Company of Massachusetts," whereas said assignee should have been described and specified as *Rockwood Sprinkler Company of Massachusetts*, as shown by the records of assignments in this office; and that the said Letters Patent should be read with this correction therein that the same may conform to the record of the case in the Patent Office.

Signed and sealed this 24th day of November, A. D., 1914.

[SEAL.]

R. F. WHITEHEAD,

Acting Commissioner of Patents.
